UNITED STATES PATENT OFFICE.

JOHN A. WHITTINGTON, OF ATLANTA, GEORGIA.

COLOR-PRINTING DEVICE.

1,378,435.

Patented May 17, 1921.

Application filed June 11, 1920. Serial No. 388,133.

To all whom it may concern:

Be it known that I, JOHN A. WHITTINGTON, a citizen of the United States, residing at Atlanta, in the county of Fulton and State of Georgia, have invented certain new and useful Improvements in Color-Printing Devices; and I do hereby declare the following to be a full, clear, and exact description of the invention, such as will enable others skilled in the art to which it appertains to make and use the same.

The object of the invention is the provision of the device intended to be set up in type, cuts, and the like, for the purpose of placing a spot of desired color and design in the printed matter and of different color from the printing ink used for attracting the attention of the reader's eye to an advertisement or other matter in which the spot is located.

It is the object of the invention to provide such a device which will place a spot of different color than the printing ink used on the paper or sheet at the same time that the printing is done or the impression made, thereby eliminating the necessity for separate printing operations.

A further object is the provision of such a printing device having a wick or equivalent means for placing the spot or figure on the paper at the time that the impression is made, with novel means for mounting said wick and supplying it with ink.

A still further object is the provision in such a device of novel means for protecting the wick or similar means from the application of ink thereto from the inking rollers or device of the printing press, and to also print a circle or border around the spot or figure in the ordinary ink, thereby providing a contrast, giving a neat and attractive appearance.

It is also the object to provide a device which is simple and inexpensive in construction, and which can be used and readily set up with type, cuts, and the like.

With the foregoing and other objects in view, which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawing, wherein:—

Figure 1 is a plan view of the device.

Fig. 2 is a diametrical section thereof showing same in contact with the inking roller.

Fig. 3 is a similar view showing the device bearing against the platen to make the impression, portions being shown in elevation.

Fig. 4 is a view showing the impression that is made by the device, including the central spot or figure of different color, and the surrounding ring or border of a color according to the ink used in printing.

The device comprises an ink reservoir or chamber 6 of any suitable shape, having a top or cap 7, and said reservoir is less than type high, so that the top thereof will be below the surface of the type. The top 7 has an annular depending flange 8 screw 75 threaded within the reservoir and providing a detachable connection, and said top has an aperture 9 in order to fill the reservoir with the colored ink used for printing the spot or figure.

Slidably vertically within a central opening 10 in the top 7 is a shielding and printing sleeve 11, having an outstanding annular flange 12 at its lower end to contact with the top 7 and limit the upward movement 85 of said sleeve. A tube 13 is disposed centrally within the reservoir, and has an out-turned annular flange 14 at its lower end seating on the bottom of the reservoir, and said tube has its upper end projecting 90 through the opening 10 into the sleeve 11, so that said sleeve is slidable on said tube. A wick 15 is disposed within the tube and supported thereby, and said tube and wick are type high, so that the upper end of the wick will contact with the paper or sheet when the impression is made. The tube 13 has apertures 16 in the wall thereof below the sleeve 11 so that the ink will flow to the wick 15 for saturating it and raising the 100 ink by capillary attraction to the upper end of the wick, to keep same moistened.

The sleeve 11 is yieldingly raised by means of a coiled expansion spring 17 surrounding the tube 13 and confined between the flanges 12 and 14, thereby forcing the sleeve upwardly and normally bringing the flange 12 against the top 7 of the reservoir

when the sleeve 11 is unobstructed. When the device passes with the type under the rubber or other soft inking roller 20, the upper end of the wick 15 or equivalent means is prevented from contacting with the surface of the roller, due to the fact that the tension of the spring 17 will raise the sleeve 11 with sufficient force, in order that when the device passes under the roller, the sleeve 10 11 is only depressed a limited amount, and the tension of the spring 17 will compress and raise the rubber or material of the roller above the wick 15, thereby preventing contact, as seen in Fig. 2. The sleeve 11 is thus 15 forced into the roller, to prevent it from contacting with the wick, and upper end of the tube 13. This will apply the ink from the roller to the upper end of the sleeve 11. The sleeve thus serves as a shield for the 20 wick, and when the device passes under the platen 21 against which the paper or sheet rests, the platen being unyielding, will depress the sleeve 11 so that the paper or sheet will press against the upper end of the wick 25 15. Thus, when the main impression is made on the sheet, a spot or figure 23 is placed on the sheet by the upper end of the wick, and the ink on the sleeve 11 prints a circle or border 22 around said spot or figure. The 30 tube 13 and wick 15 can be of various shapes to print a spot or figure of desired outline or design, and the sleeve 11 can also be of various forms. The border 22 will be of the 35 color of the ink applied by the roller 20 to the type, while the spot or figure 23 can be of red or other distinctive color, to attract attention to the advertisement or printed matter in which the spot or figure is used. The device can be used for newspapers, magazines and other periodicals, as well as for 40 job printing.

Having thus described the invention, what is claimed as new is:—

1. A color printing device comprising a 45 reservoir having a top, ink applying means leading from within the reservoir through

the top, a yieldable shield movably mounted within said top to force a soft inking roller away from said means.

2. A color printing device comprising an 50 ink applying means including a wick, a slidable sleeve surrounding said wick to force a soft inking roller away from the wick, and an expansion spring surrounding the wick and bearing against said sleeve to 55 yieldingly project the sleeve.

3. A color printing device comprising a tube, a wick in the tube, a sleeve slidable on the tube for forcing a soft inking roller away from said wick, and a coiled expansion 60 spring surrounding the tube and confined between said sleeve and tube.

4. A color printing device comprising an ink reservoir, ink applying means including a wick extending from said reservoir, and a 65 shield slidable in said reservoir for forcing a soft inking roller away from the wick.

5. A color printing device comprising a reservoir for ink, a tube in the reservoir, a wick within the tube saturated by the ink in 70 the reservoir to apply the ink from one end of the wick, and a yieldable sleeve slidable on the tube for forcing a soft inking roller away from said end of the wick.

6. A color printing device comprising an 75 ink reservoir, having an opening in the top thereof, a tube seating on the bottom of the reservoir and having apertures for the passage of ink, a wick in said tube to be saturated by ink for applying the ink from the 80 upper end thereof, a sleeve slidable in said opening on the tube, and an expansion spring between said tube and sleeve for yieldingly raising the sleeve to force a soft inking roller away from the upper end of said wick. 85

In testimony whereof I have signed my name to this specification in the presence of two subscribing witnesses.

JOHN A. WHITTINGTON.
